MACHINE FOR AND METHOD OF BUILDING HEELS

Filed March 1, 1928

UNITED STATES PATENT OFFICE

FRED HAWKINS, OF EVERETT, MASSACHUSETTS

MACHINE FOR AND METHOD OF BUILDING HEELS

Application filed March 1, 1928. Serial No. 258,157.

This invention relates to the art of heel building, and is directed to the provision of a novel apparatus for and method of building whole lift heels and nailing the lifts of each 5 heel together in a continuous operation.

The invention is an improvement on the method of building heel blanks, and in the machine and devices used for practicing such method, disclosed in the prior patents to 10 Mitchell & Parks, No. 1,399,508, dated December 6th, 1921, No. 1,403,184, dated January 10th 1922, and No. 1,432,080, dated October 17th 1922, and the patent to Parks, No. 1,451,469, dated April 10th, 1923.

15 In building heels with the machines and according to the method disclosed in these patents, pasted lifts are assembled to form a heel blank; a combined heel former and separator such as shown in the Parks patent 20 above referred to is placed against the heel blank, a new heel blank is formed, and the process continued, and with each formation of a heel blank, said blank and its separator are forced into a heel log container which is 25 of a size to offer frictional resistance to the column of heel blanks and alternating formers and separators, so that as the heel blank at the end of the column is discharged from the container, the lifts will have been firmly 30 pressed together and the paste will have had time to set. In the preferred embodiment of the invention, each of the combined heel formers and separators is provided with a head which works in a groove in a race-way, 35 one part of which forms the upper wall of the heel log container, so that the series of formers and separators are continuously moved over the race-way in a manner to be successively returned to the front of the machine, where they may be again employed to 40 be interposed between the heel blanks as they are formed.

The Mitchell & Parks machines of the type referred to have been, and are being, extensively used and are highly satisfactory. The 45 only objection to this machine is the large number of heel former plates that are required to accommodate the different sizes and shapes of tapered heels. For example, a set 50 of from forty to fifty individual heel formers

is required for each different size, height, wedge, and taper of heel; thus necessitating a very large assortment of formers in order to enable the machine to handle a complete line of tapered heels. These formers are necessary not only for providing proper pressure upon the heels as they go through the heel log container, but also for holding the lifts in each heel in proper position while the paste 55 is setting.

According to my invention, I provide mechanism for inserting a nail into the assembled heel blanks simultaneously with the movement of the machine which forces the heel blank into the heel log container, and by this means, securely anchor the lifts in a fixed position while the paste is still moist; i. e. before it has had time to set. By thus 60 permanently securing the lifts together and in proper position at the beginning of the 65 passage of the heel blank through the heel log container, the only function necessary to be performed by the former plates is to equalize the wedge in the heel. Since it is only necessary for the plates to conform to three or 70 four different wedges, and since they do not have to conform to different heights and shapes of heels, it will be seen that the number of complete sets of plates required in the 75 practice of my invention is greatly reduced over what would be required in practicing the Mitchell-Parks method as disclosed in the foregoing patents. In other words, the forming function of the plate is of relatively little 80 importance, inasmuch as it becomes no longer necessary for the plate to engage the rounded surface of the heel blank to prevent the lifts 85 from moving out of position.

The only other comparable method in extensive use within my knowledge is that known as the Grover method, in which the lifts, pasted on both sides, are assembled horizontally in a mold, and a nail is driven into the heel through a slot in the bottom of the mold. Before the nail can be driven, the operator swings an arm over the heel and forces down an iron block which holds the heel down while the nail is being driven upward through it. The operator then swings 90 the arm back to its position, takes the heel out 95 100

of the mold, and puts it on a board, which is provided with slopes to equalize the wedge in the heels. When a number of heels have been placed on this board, they are put under a 5 jack-press and held under pressure for several hours to allow the paste to set.

It will be seen that considerable time is required for swinging the arm over the heel and back to its former position, for removing the 10 heel from the mold, and for putting the heels into the jack-press.

My improved method eliminates the disadvantages of the Grover method, since it provides for driving the nail into the heel as the 15 heel is being forced automatically into the heel log container, none of the operator's time being lost on account of the nail-driving operation, or in the removal of the heel from the building table.

20 Having thus outlined the purposes and advantages of my invention, I will now proceed to describe the same in detail, referring to the accompanying drawing, in which—

25 Figure 1 is a view in side elevation of a Mitchell & Parks heel building machine equipped with my nail-driving mechanism;

30 Figure 2 is an enlarged view, partly in section and partly in side elevation, of the front, or left-hand, end portion of the machine shown in Fig. 1;

35 Figure 3 is a top plan view of the parts shown in Fig. 2, omitting the race-way and showing the nail-driver in its retracted position;

40 Figure 4 is a similar view showing the nail-driver in its advanced position and illustrating a nail driven thereby into a heel blank;

45 Figure 5 is a section taken on the line 5—5 of Fig. 3 directly in front of the supporting block against which the heel blanks are built up to show the provision of two nail-holding apertures, or guides, in either of which a nail to be driven may be placed according to the size of the heel blank to be nailed, the apertures being arranged in a vertical plane for use when making whole-lift heels; and

50 Figure 6 is a similar view with the two nail-holding apertures or guides arranged in a horizontal plane for use when making pieced lift heels.

55 Referring now to the drawing, the numeral 1 indicates the frame of the machine the top portion of which is inclined forwardly as shown and has supported thereon a combined heel-log container and race-way. The race-way is indicated at 2 and comprises two parallel bars having rounded connections at either end and provided with a continuous slot 3 (Fig. 2) in which are slidably mounted the heads 4 of a set of plates 5. In the present instance, these plates, so far as function is concerned, are properly only equalizing plates; that is to say, the incline of the face 60 of the end portion 6 thereof being such as to

compensate for the wedge of the particular type of heel being produced. Below the race-way 2 and parallel with the lower side thereof is a bed-plate 7 which co-operates with the lower member 8 of the race-way to provide the heel-log container. The plate 7 is what is known in the art as a breast plate, that is to say, the breasts of the heels rest upon it as they pass through the container.

70 In operation, as the column composed of heel blanks and equalizing plates is forced through the heel log container, each heel blank, in turn, at the forward end of the column will fall away while the plate will continue around the race-way and slide down the upper side thereof, all as clearly shown in Fig. 1. The driven part of the machine comprises a shaft 9 driven by a pulley 10 and having mounted thereon an eccentric 11. Encircling the eccentric 11 is a strap 12 having a head 13 in which is mounted one end of an actuating rod 14 provided on its upper side near its lower end with a recess 15 affording a shoulder 16. The actuating rod 14 rests at its lower side on a roller 17 mounted intermediate the ends of a lever 18 which is pivoted at its lower end, as indicated at 19, on the frame of the machine. Pivoted at 20 on the lever 18 above the actuating bar 14 is a dog 21 the lower or free end of which is normally held in contact with the upper side of the bar 14 by means of a leaf spring 22. As shown by Fig. 1, in the normal position of the parts, the free end of the dog 21 extends beyond the shoulder 16 on the actuating bar when the latter is in its extreme inward position, or that shown in the figure. The lever 18 is moved outwardly or away from the operator to bring the dog 21 to a position where its free end will fall into the recess 15 and be engaged by the shoulder 16 on actuating rod 14 through the medium of a treadle 23 pivoted at its upper end at 24 on the frame, to which is pivotally connected one end of a connecting rod 25, the other end of which has a slotted engagement 26 with a pin 27 on the lever 18 at any suitable point above its pivot 19. The operator, by placing his foot on the treadle 23, pushes it outward, causing the connecting rod 25 to move the upper end of the lever 18 in the same direction, whereby the free end of the dog 21 will be moved over and fall into the recess 15, and in the next outward movement of the actuating bar 14 caused by the rotation of eccentric 11, the shoulder 16 on the actuating rod will engage the free end of the dog and move the upper end of the lever 18 to its extreme outward position.

100 In this movement the assembled lifts will be forced against the previously formed column of heel blanks in the heel log container, a nail will be driven through the assembled lifts, and said lifts, together with the column of lifts in the container, will be 105 110 115 120 125 130

125 130

advanced a given distance therein. These operations result from the mechanisms actuated by the lever 18 which will now be described.

5 The numeral 28 indicates a head which is slidably mounted on a rear extension of the bed, or breast plate, 7, and is equipped with side jaws 29 for properly positioning the lifts, and at its forward end, with a supporting block 30. Mounted in the supporting block to have its forward end lie flush with the forward face of said block is a circular nail-holder and guide 31 which, as shown more particularly in Fig. 5, is provided with 10 two apertures 32, 33 extending longitudinally thereof and one or the other of which is adapted to receive the nail to be driven into the assembled lifts or heel blank. Such a nail is shown by dotted lines in Fig. 3 and 15 indicated by the numeral 34. The nail-holder 31 is held in position in the supporting block by means of a set screw 35 (Fig. 2). As shown by Fig. 5, the aperture 32 is located directly over the aperture 33 and this 20 arrangement is for the purpose of permitting the operator to use one or the other of said apertures for receiving the nail to be driven, according to the size of the heel being made, so as to enable the nail to be driven approximately centrally through the heel. The 25 head 28 at the rear of the supporting block 30 is provided on either side with apertured lugs 36 in which are mounted bearings for receiving the upper ends of a yoke member 37 (Fig. 5) which, at its lower side, has an arm 38 projecting forwardly therefrom and pivotally secured at its forward end, as indicated at 39, to the upper end of the lever 18. It will thus be seen that as the upper 30 end of the lever 18 is moved forward by the action of the rod 14, the sliding head 28 will be moved forward or outwardly over the breast plate 7 so that the lifts assembled against the supporting block 30 will be forced 35 into engagement with the separator plate 5 placed on the heel blank previously formed, as clearly shown in Fig. 2.

As previously indicated, it is the main purpose of my invention to drive a nail into the 40 assembled lifts concurrently with the advance thereof under the action of the sliding head, as above described. To this end, I provide the following mechanism:

Mounted on the sliding head 28 is a metal 45 block 40 which is adapted to have a sliding fit in a groove 41 formed on the upper side of said head. Mounted at one end in the block 40 are two metal rods 41, 42, respectively (Fig. 2) which are positioned to work in the apertures 32, 33 of the nail-holder 31, and which, with the block 40, constitutes a nail-driver. The block 40 is transversely grooved 50 on its upper side, as indicated at 43 in Figs. 3 and 4, and in which groove works an anti-friction roller 44 mounted on the inner end

and underside of an arm 45 which is pivotally mounted about centrally of its length at 46 on the sliding head 28. The outer end of the arm 45 is provided on its underside with an anti-friction roller 47 which moves between and is adapted to engage one or the other of two fixed stops 48, 49, respectively, adjustably secured on the side of the frame of the machine. In the position of the parts just described shown in Fig. 3, the sliding head 28 has been moved to the limit of its rear or retracted position, the roller 47 has engaged the stop 48 prior to the termination of this movement, and the block 40 has thereby been moved to the rear to withdraw the nail-drivers 41, 42 from the apertures 32, 33. The ends of the nail-drivers, however, do not leave said apertures but remain supported in the rear portions thereof.

Assuming, now, a heel blank to have been assembled on the breast plate 7 between the jaws 29, as shown in Fig. 4, the operator places his foot on treadle 23 and pushes it outwardly, thereby moving the new heel blank toward the separator plate of the preceding heel blank in the container and permitting the shoulder 16 on the bar 14 to engage the dog 21 in the manner previously described. As the sliding head 28 is now moved outwardly, the whole column of lifts in the heel log container must be moved and such movement is resisted by frictional engagement of the column with the container. The lifts on the new heel blank are thus pressed firmly together and concurrently with this operation, the roller 47 will be brought into engagement with the stop 49, as shown in Fig. 4, thereby causing the block 40 carrying the nail-driver to be advanced at a greater rate of speed than the head 28, which results in a nail, which has been previously inserted in one or the other of the apertures 32, 33, being forced into the assembled lifts at about the time the sliding head reaches the limit of its outward movement. In the return movement of the sliding head, which is effected by gravity, the roller 47 will engage the stop 48 and cause the retraction of the nail-driver, as previously described.

To provide for the release of the dog 21 from the shoulder 16 in the inward movement of the actuating bar 14, I provide the following mechanism:

Pivotally mounted on the pivot 20 of the dog 21 is a short arm 50 which is normally held against a fixed stop 51 on the frame by the other side of leaf spring 22 which, to this end, engages a pin 52 on the arm 50. The outer end of the arm 50 is provided with an inclined lug 53 which normally rests against the underside of the stop 51. The connection between the arm 50 and dog 21 at the pivot is such as to allow only a slight independent movement of one relative to the other.

When the upper end of lever 18 is moved in the forward direction, the lug 53 will be moved from under stop 51, and the spring 22 will throw the inner end of said arm with said lug upward to the limit of its movement. In the return movement of the lever 18, the bottom side of lug 53 will ride over stop 51 and raise the inner end of arm 50 which thereby causes the inner end of dog 21 to be raised out of the slot 16 or to the position shown in Fig. 1. This mechanism is described in the interest of a clear understanding of the operation of the machine, but it forms no part of the present invention.

Referring to Fig. 1, the short arm 54 connected at one end to the lever 18, the rod 55, and a member 56 actuated thereby, form parts of mechanism for insuring the fall over the rounded forward end of the race-way of only one separator plate at a time, but as this mechanism forms no part of the present invention, it need not be more particularly described.

So far as the method involved in my invention is concerned, it is characterized by the novel steps of inserting a nail into the assembled lifts concurrently with the movement of the head toward the pressure container, and completing the driving of the nail simultaneously with the entrance of the heel-blank into the pressure container and into contact with the column of heel-blanks therein, so that sufficient resistance is offered to the movement of the new heel-blank to permit the nail to be driven through the lifts thereof.

In the modification shown in Fig. 6, the nail-holding apertures indicated by 32^a and 33^a are arranged in a horizontal plane, and in this arrangement a nail is inserted in each of the apertures and when driven into the heel-blank, are so positioned that they will enter the same on either side of the dividing line between the two pieces of the lift.

To enable either the horizontally or vertically disposed apertures to be employed, the block 40 can either be provided with four drivers, two of which are vertically disposed to enter the apertures 32 and 33 and the other two horizontally disposed to enter the apertures 32^a and 33^a, or else interchangeable nail-drivers, the one provided with two vertically disposed drivers and the other with two horizontally disposed drivers, could be employed.

In the drawings, it is deemed sufficient to show one arrangement of nail-drivers, that adapted to enter the vertically disposed apertures, as it will be perfectly clear that the only change to adapt the drivers for use with the horizontally disposed apertures is to arrange the drivers in a horizontal position, a matter which will be well understood by those skilled in the art.

I claim:

1. In a machine for building heels, in combination with a heel-log container, a sliding

head against which the lifts for the heels are assembled and by the movement of which the assembled lifts are forced into the container, a nail-holder carried by the head, a nail-driver co-operating therewith, means for moving said head toward the container, and automatic means for operating the nail-driver simultaneously with the movement of the head, whereby to drive a nail into the assembled lifts while the head is still in contact therewith. 70

2. In a machine for building heels, in combination with a heel-log container, a sliding head against which the lifts for the heels are assembled and by the movement of which the assembled lifts are forced into the container, a nail-holder carried by the head, a nail-driver co-operating therewith, means for moving said head toward the container, and means for advancing the nail-driver simultaneously with the movement of the head but at a greater rate of speed, whereby to drive a nail into the assembled lifts while the head is still in contact therewith. 75

3. In a machine for building heels, in combination with a heel-log container, a sliding head against which the lifts for the heels are assembled and by the movement of which the assembled lifts are forced into the container, a nail-holder carried by the head, a nail-driver slidably mounted on said head and co-operating with the nail-holder, means for moving said head toward the container, and means for advancing the nail-driver over the head simultaneously with the movement of the head but at a greater rate of speed, whereby to drive a nail into the assembled lifts while the head is still in contact therewith. 90

4. In a machine for building heels, in combination with a heel-log container, a sliding head against which the lifts for the heels are assembled and by the movement of which the assembled lifts are forced into the container, a nail-holder carried by the head and having a plurality of nail-apertures therein, a nail-driver co-operating with said nail-holder and comprising a plurality of driving members positioned in said apertures, means for moving said head toward the container, and automatic means for operating the nail-driver simultaneously with the movement of the head, whereby nails inserted in said apertures will be driven into the assembled lifts while the head is still in contact therewith. 100

5. In a machine for building heels, in combination with a heel-log container, a sliding head against which the lifts for the heels are assembled and by the movement of which the assembled lifts are forced into the container, a nail-holder carried by the head and having a plurality of nail-apertures therein, a nail-driver mounted to slide longitudinally of the head and comprising a plurality of driving members positioned in said apertures, means for moving said head toward the 110

container, and automatic means for causing the advance of the nail-driver simultaneously with the movement of the head but at a greater rate of speed, whereby to drive a nail positioned in one or the other of said apertures into the assembled lifts while the head is still in contact therewith.

5 6. In a machine for building heels, in combination with a heel-log container, a sliding head against which the lifts for the heels are assembled and by the movement of which the assembled lifts are forced into the container, a nail-holder carried by the head, a nail-driver slidably mounted on said head and co-operating with said nail-holder, an arm pivotally mounted on said head and having one end operatively engaging said nail-driver and the other end free, means for effecting a movement of said head toward the container 10 and its return to its initial position, and a pair of stops mounted on the machine and between and into engagement with which the free end of said arm is moved, whereby in the forward movement of the head one of said 15 stops will be engaged by the free end of said arm, to cause the nail-driver to be advanced at a greater rate of speed than the head and thus drive the nail into the assembled lifts while the head is in contact therewith, and 20 whereby in the return movement of the head the other stop will be engaged by the free end of said arm and return the nail-driver to 25 its initial position.

7. The method of building heels, which 30 consists in assembling a series of pasted lifts to form a heel-blank, forcing the heel-blank into a zone of frictional resistance, and simultaneously with the entrance of the heel-blank into said zone inserting a nail therein.

40 8. The method of building heels, which consists in assembling a series of pasted lifts to form a heel-blank, advancing the heel-blank toward and forcing it into and through a zone of frictional resistance, and during 45 the movement of the heel-blank initiating the driving of a nail therein and completing such operation simultaneously with the entrance of the heel-blank into said zone of frictional resistance.

50 In testimony whereof, I have hereunto set my hand.

FRED HAWKINS.
